UNITED STATES PATENT OFFICE.

EDWARD J. SCHREMP, OF ROCHESTER, NEW YORK.

PRESSING MACHINE FOR GARMENTS AND THE LIKE.

Application filed June 4, 1924. Serial No. 717,704.

REISSUED

This invention relates to improvements in machines for the ironing or pressing of garments and fabrics, of the power-press type, and has for its purpose to produce a 5 machine of this type which will operate in an improved manner particularly with reference to the delivery of the goods into position to be operated upon whereby the feeding of the machine is materially facilitated 10 with a resulting desirable increase in output.

Important features of the present invention, which contribute to the rapidity and ease of operation, consist of an improved arrangement employing double sliding trays 15 operatively connected and supported to be moved alternately into and out of pressing position and further in the provision of means actuated by the movement of the trays into pressing position and operating automatically to control the operating force for 20 the pressing head whereby the latter will be depressed to perform the pressing operation. My improved construction accordingly provides the desirable arrangement whereby 25 by the movement of the respective work supporting trays into position for pressing will automatically operate to control the pressing mechanism without requiring other and special manipulation to effect the lowering of 30 the pressing head. The operation of the machine is accordingly materially simplified and the capacity of the machine correspondingly increased. To allow of the operation in the manner as described, the operating 35 connections arranged to be actuated by the trays, are of a construction and arrangement to permit of the independent manipulation of the power controlling means whereby the pressure control may be released or reversed 40 by manual or other operation when the pressing of the garments is completed.

The described and other features and advantages of my present improvements will be more fully understood by reference to the 45 accompanying drawings wherein like reference characters are applied to the corresponding parts in the several views.

Referring to the drawings:

Fig. 1 is a view of a pressing machine embodying the features of my invention and shown in side elevation.

Fig. 2 is a plan view thereof with the pressing head omitted.

Fig. 3 is a view in front elevation showing 55 the improved arrangement of the delivery trays and supporting tracks therefor.

Fig. 4 is an end elevation of the track supporting bracket.

In the approved construction as herein illustrated, the improved features of my invention are illustrated incorporated or associated with a power type of pressing machine employing steam as the operating force for the pressing head. The pressing machine, as shown, comprises a suitable supporting standard 1 having mounted thereon the usual rigid or stationary support 2 for the stationary buck or pressing member 3. For cooperating with the fixed pressing member or buck there is provided a movable pressing head 4 mounted upon a supporting pressure arm 5 suitably journaled upon the standard at 6 and provided with a depending operating arm or extension 7 formed integrally with the arm 5. The pressure arm 5 is operated by a steam cylinder 8 provided with an operating piston 9 and piston rod 10 pivotally connected at 11 to the pressure lever 7. The piston rod 10 is shown as provided with an articulated member portion 12 75 to compensate for the arc of movement of the pivotal connection 11. As will be readily understood by admitting steam within the cylinder 8 to one side or the other of the piston it will accomplish the movement of 80 the latter for depressing the pressure head upon the buck or stationary pressing member 3 or will move the pressing head into the elevated or open position, as shown in Fig. 1. The steam is admitted within the cylinder for this purpose through the intakes 14-15 from a suitable supply pipe under the control of a two-way control valve 16 having an operating lever 17. For manually actuating the control valve 16 suitable operating connections are provided which, as shown, consist of a vertical lever arm 20 pivotally supported at 21 and pivotally connected by a link 22 to the valve arm 17 and an operating link 23 pivotally connected to 85 the upper end of the lever 20 and expanded forwardly with a sliding bearing in the supporting bracket 24 and provided with an externally positioned handle 25 for manual operation.

In accordance with the present invention a double sliding tray structure is provided for the purpose of receiving garments or articles to be pressed and for moving them into position super-imposed above the stationary pressing board or buck 3 in the desirable arrangement whereby the delivery

110

trays are supported and connected to be moved reversely so as to be alternately in pressing position and in an outer position for the removal of the finished article and 5 for receiving thereon another garment to be pressed. This arrangement is particularly advantageous in that it allows the operations of taking off the finished article and 10 positioning of a new article upon one tray being performed during the period of pressing as related to the other of the trays.

The respective trays are indicated at 30 and 31 and are each composed of rectangular frames 32 to which is attached a panel 33 15 of canvas or other suitable flexible material adapted for receiving the garments and to flexibly support them between the pressing members 3 and 4, which as will be understood are desirably of flexible construction 20 and suitably heated for properly pressing or ironing of the goods. Each of the trays is provided with rollers operating upon suitable tracks to guide the travelling movement thereof. As shown the tray 30 is provided 25 with rollers 34 suitably journalled upon shaft extensions at each corner thereof, the rollers 34 being grooved and fitted to ride upon oppositely positioned tracks 35 supported upon brackets or frame supports 24 30 and at their rearward ends upon the standard of the pressing machine.

The other and uppermost tray 31 is similarly provided with four supporting rollers 36 journalled upon suitable lateral extending axles 37, the rollers being grooved and fitted to ride upon oppositely positioned movable tracks 38. The tracks 38 are pivotally supported at their forward ends upon the brackets 24 and at their rearward end 40 portions are supported upon the compression springs 40—40 operating normally to elevate the tracks. The respective trays are connected to be moved in unison by means of oppositely positioned and similarly arranged cables 41—42 connected to the respective trays and passed over forward and rearward pulleys 43 and 44 journalled upon suitable bearings mounted upon the frame members 24 and the machine frame of standard 1. The described arrangement provides 50 that the trays shall be movable reversely in unison, the tray 30 which is the lower tray, being movable upon the fixed tracks 35 which are positioned at the proper height 55 to be movable over the buck 3 of the pressing machine in close proximity and operating relation thereto. The upper tray 31 is movable in a path above that of the tray 30 whereby the latter passes thereunder and 60 when the upper tray 31 is in pressing position above the buck 3, upon lowering of the pressing head 4 the upper tray 31 will be depressed together with its supporting tracks against the influence of the springs 40 during the pressing of the garment.

In further accordance with the present invention it is provided that the pressing head shall be automatically lowered as the trays are successively brought into operating or pressing position. For this purpose suitable valve operating connections are provided and arranged to be actuated by engagement therewith of the trays, or of parts movably connected therewith, when the trays are moved into the position for 75 pressing or in superimposed relation to the stationary buck 3. The connections as here illustrated comprise a bell crank lever 46 suitably fulcrumed at 47 upon the standard 1 the upper arm of said lever being extended into the path of the trays to be engaged thereby during the final period of their movement and the lower arm of the bell lever 46 being pivotally connected at 47 to a connecting link 48 connected to the lever 80 20. To allow for the independent and manual operation of the steam controlled valve 16 for the release of the pressure and raising of the pressing head the connection between the connecting link 48 and the lever 90 20 is of a resilient or yielding character which allows of the operating link 23 being shifted rearwardly for reversing the steam without movement of the actuating lever 46 which, as will be noted, is held from reverse 95 movement until the tray is retracted. The resilient connection provided consists of the arrangement whereby the forward end of the link connection 48 is passed freely through an eye of a bracket 49 attached to the lever 20 and provided with a retaining nut 50 upon its outer end. The link 48 has affixed thereon a bearing collar 52 and a coil spring 53 is fitted upon the connecting link or rod 48 interposed between the bearing collar 42 and the bracket 49. The construction thus provided allows of the manually operating connections being shifted to reverse the valve 16 against the influence of and by the compression of the spring 53 and accordingly independent of the movement of the automatically actuated connections.

As will be understood from the foregoing and the operation of the machine the operator arranges the articles to be pressed upon the outwardly positioned tray during the period that the pressing is being performed upon the other tray then advanced within the pressing machine proper. Upon completion of the pressing operation the operator presses the handle 25 inwardly or to the right as illustrated in Fig. 1, thereby reversing the steam pressure to elevate the pressing head. Upon then manually shifting or sliding the trays the unpressed garment is advanced to the pressing machine and the finished garment upon its tray retracted and during the final interval of the tray movement the advancing tray will actuate the lever 46 so as automatically to 120 125 130

effect the reversal of the steam and depressurizing of the pressure head.

While I have illustrated an approved embodiment of the features of my invention it will be understood that various modifications 5 may be made therein without departing from the scope of the invention as defined in the appended claims.

Having described my invention I claim:

10 1. An ironing or pressing machine for garments and the like having in combination with the buck and the pressing head movable with relation thereto: a power means connected to the head for operating the same, a controlling means connected with the power means operative to control the movement of the power means, a work supporting tray 15 slidable on guides for movement into and out of operative relation with the buck and 20 pressing head, and actuating connections for the controlling means in the path of movement of the tray arranged to be actuated upon the movement of the tray into operating or pressing position to effect the lowering 25 of the pressing head and said actuating connections being provided with means to permit the controlling means being actuated independently thereof.

2. An ironing and pressing machine for 30 garments and the like having in combination with the buck and the pressing head movable with relation thereto: a power means connected to the head for operating the same, controlling means connected with the power 35 means operative to control the movement of the power means, a work supporting tray slidable on guides for movement into and out of pressing position, an actuating connection for the controlling means comprising a lever positioned to be engaged by the tray when moved into pressing position and 40 connections from said lever to the controlling means including a yieldable element adapted to permit the controlling means

being moved independently of the actuating 45 lever and independent actuating means connected to the controlling means.

3. An ironing and pressing machine for garments and the like having in combination with the buck and the pressing head movable 50 with relation thereto: work supporting trays slidable on guides for movement into and out of position alternately between the head and buck and connected with each other so that movement of one tray in one direction 55 will cause movement of the other tray in an opposite direction, stationary tracks supported to guide the movement of one of the trays into pressing position beneath the head and tracks for guiding the movement of the 60 other tray, said latter tracks being resiliently supported to be movable to support its tray to normally pass above the other tray and to permit its tray being depressed when moved beneath the head into pressing position. 65

4. An ironing and pressing machine for garments and the like having in combination with the buck and the pressing head movable with relation thereto: work supporting trays 70 slidable on guides for movement into and out of position alternately between the head and buck and connected with each other so that movement of one tray in one direction will cause movement of the other tray in an opposite direction, stationary tracks supported to guide the movement of one of the 75 trays into pressing position beneath the head and said tracks being pivotally supported at their forward ends and resiliently supported at their inward ends thereby to be movable 80 to support its tray to normally pass above the other tray and permit of its tray being depressed by engagement therewith of the pressing head. 85

Signed at New York in the county of New York and State of New York this 13th day of May A. D. 1924.

EDWARD J. SCHREMP.
